[57] ABSTRACT

A word forming game device includes a board having a playing surface and a rotor disposed thereover. The playing surface is marked with seven concentric circles connected by 32

radial lines to form 192 segmental spaces in 32 radially disposed groups or sectors of six each and in six circumferential groups or concentric rings of 32 each. The spaces in the outermost ring severally have numerical symbols arranged in numerical sequence to designate the corresponding radial groups therebelow, while the spaces in the remaining rings severally have specific alphabetical letter symbols or a "WILD" word symbol designating any desired letter, but normally do not form words either radially or circumferentially, and the spaces in the outermost ring severally are provided with upstanding stops along the radial lines. The rotor is in the form of a circular disc covering all but the outermost ring of spaces and provided with a sector-shaped slot rotatable to expose upon stopping all five spaces in each of the radial groups, but only four spaces in each of the five concentric circumferential groups, totaling 20 letter symbols and/or "WILD" symbols. A radial group of letter symbols is provided along each side of the slot in alignment with the exposed circumferential groups and spelling one or more words radially inwardly, such as the word "WHEEL" on one side and the words "A WORD" on the other side, to designate the preferred radially inward sequence of selecting the symbols in each of the five circumferential groups upon successive rotations and stops of the rotor, which also is provided along the side of the slot designated by the word "WHEEL" with a detent extending beyond the rotor periphery and engageable with the stops to stop the rotor between adjacent pairs of stops to positively designate the first symbols of the circumferential groups to be selected sequentially radially inwardly. As the rotor stops upon successive rotations, the four symbols in each of the five exposed circumferential groups are selected by each player until all 20 symbols are selected to form words by the use of playing pieces having corresponding symbols.

WORD FORMING GAME DEVICE

BACKGROUND OF THE INVENTION

1. Field of the Invention

This invention relates to improvements in word forming games, and more particularly to a new and improved device for use in playing a word forming game.

2. Description of the Prior Art

While there are a wide variety of word forming games in use, such as "SCRABBLE," there are none, to this inventor's knowledge, employing a device for determining the random selection of a predetermined number of letters from which words are to be formed in accordance with certain rules, other than possibly the device shown and described in U.S. Pat. No. 156,212 of 1874. In this patented device, there is a box having compartments for playing pieces bearing the letters of the alphabet and composing sticks for holding the same, while the hinged box cover or lid is provided on its underside with a single ring dial divided into 26 segmental spaces, one for each letter of the alphabet, and pivotally mounted at the center of the ring is a spinnable pointer. The game is played by any number of persons, with the conductor of the game spinning the pointer to designate on stopping a single letter which he selects from the playing pieces and places in the composing stick. This operation is repeated until six letters are obtained and placed in successive order, whereupon the completed stick is given to a player. In a similar manner, each player is provided with a composing stick having six letters and endeavors within a set time to form a grammatical sentence of six words beginning with the letters given in the order selected.

While such game can be highly entertaining and educational, it is evident that this game device is not designed for use in determining the particular letters from which words are to be formed, but merely the initial letters of words to be formed by the players themselves in the specified sequence. Further, while the patented game device could be used to determine the letters of the words to be formed, the limited capability of the pointer to designate but one letter per spin takes excessively long to determine the letters to be used, and readily could result in loss of interest by the players. Moreover, excessive repetition of letters on successive spins could prevent the formation of words and thereby defeat the desired purpose.

SUMMARY OF THE INVENTION

Accordingly, it is a primary object of the present invention to provide a new and improved device for use in playing a word forming game, which device is so constructed and designed as to possess the advantages of "SCRABBLE" wherein each player obtains the same number, but different letters, and of the patented device, while eliminating their disadvantages by facilitating the designation of the same letters to be used by each competitor in forming words from such letters for both entertaining and educational purposes, and by virtue of the operation of which device, each player starts on an equal basis, in the word forming ingenuity contest. To this end, the inventive word forming game device includes a board having a playing surface provided with a plurality of concentric circles and radial lines defining spaces between such circles and lines, and a rotor disposed over such playing surface and being rotatable to designate upon stopping radial and concentric circumferential groups of such spaces which severally have symbols therein severally indicating specific alphabetical letters or any desired alphabetical letter, whereby the designated ones of such symbols in such groups are selected to form words by the use of playing pieces having corresponding symbols.

Another object is to provide such a word forming game device wherein the symbols on the playing surface severally are in the forms of specific alphabetical letters or a characterization indicating any desired alphabetical letter, but such

symbols in any radial or circumferential group normally do not form words.

A further object is to provide such a word forming game device wherein the rotor is in the form of a circular disc having a sector-shaped slot rotatable to expose upon stopping all of the spaces of the playing surface in a number of radial groups, which number is predetermined by the number of the spaces in the concentric circumferential groups uncovered by the slot.

Still another object is to provide such a word forming game device wherein the playing surface is provided with an additional outermost concentric circle and extensions of such radial lines to define additional spaces therebetween in an outermost ring arranged beyond the outer periphery of the rotor, such additional spaces severally having symbols therein severally indicating specific numerals arranged in numerical sequence circumferentially to designate the corresponding ones of such radial groups.

Still a further object is to provide such a word forming game device wherein the rotor is provided with a radial group of symbols severally radially aligned with the symbols in the concentric circumferential groups for severally designating the radial sequence in which such latter symbols are to be selected upon successive rotations and stops of the rotor.

Another object is to provide such a word forming game device wherein the playing surface is provided with a plurality of stops severally arranged adjacent the radial lines beyond the periphery of the rotor, and the latter is provided with a detent extending beyond its periphery and engageable with the stops for positively stopping the rotor to properly designate the symbols of the groups to be so selected.

A further object is to provide such a word forming game device wherein the symbols on the playing surface are arranged in such a manner that in every designated circumferential group of symbols to be selected there is at least one symbol indicating a vowel or a characterization designating any desired letter, in order to facilitate the formation of words.

Another object is to provide such a word forming game device which is so constructed and designed as to be simple in construction, economically manufactured, easy to use, and both efficient and effective in operation.

Additional objects and advantages of the invention will become evident upon consideration of the following detailed description and accompanying drawing, wherein;

BRIEF DESCRIPTION OF THE DRAWING

FIG. 1 is an upper plan sectional view taken on line 1—1 of FIG. 3 through the cover of the box or container incorporating a preferred embodiment of the inventive word forming game device and illustrating the slotted circular rotor disc disposed in place over the indicia bearing playing surface of the configurated game board forming the base or bottom of the box;

FIG. 2 is a similar but lower plan sectional view, being taken on line 2—2 of FIG. 3 through both the cover and the game board to illustrate the complete playing surface and indicia thereon;

FIG. 3 is a sectional view taken on line 3—3 of FIG. 1 and illustrating in side elevation the detailed construction and configuration of the preferred embodiment;

FIG. 4 is an enlarged fragmentary sectional view taken on line 4—4 of FIG. 1 and illustrating the raised upper surface portion of the rotor and the manner of attaching the detent along one side of the slot, which detent is engageable with the upstanding stops on the playing surface, as shown in FIG. 1;

FIG. 5 is an enlarged fragmentary section taken along line 5—5 of FIG. 1 to show the manner in which each stop is embedded in the game board;

FIG. 6 is a view of the group of playing pieces selected upon completion of successive rotations and stops of the rotor, and FIG. 7 is a view similar to FIG. 6, but showing the playing pieces thereof after being rearranged to form words in accordance with the rules of the game.

DESCRIPTION OF THE PREFERRED EMBODIMENT

Structure

Referring to the drawings, and particularly FIGS. 1-5, a preferred embodiment of the invention word forming game device is generally indicated at 10 and preferably is in the form of a two-part box or container composed of a generally rectangular lid or cover 12 removably fitting over a similarly shaped game board 14 constituting the base or bottom of the box. The various parts of the box and its contents may be made of any suitable material such as cardboard, paperboard, wood, paper, plastic, or, where needed, metal. However, it is preferred that the cover 12 be of cardboard and the base or game board 14 be of wood.

Considering first, cover 12, it preferably is of square plan formed by a flat top wall 16 terminating at its margins in outstanding sidewalls 18 and provided in its interior with an annular spacer member 20 of square outer peripheral configuration conforming and suitably secured to the insides of top and sidewalls 16, 18 along their junctures. The interior periphery of spacer member 20 also is square, but preferably is provided with rounded corners 20a.

As for game board or base 14 it likewise is of square plan configuration with its side edges 14a forming a periphery snugly fitting within cover sidewalls 18 and its upper or inner surface 14b being provided at its margin with an annular stop member 22 having an outer square plan configuration providing an outer periphery conforming to and fitting snugly within the inner periphery of cover sidewalls 18, but an inner circular plan configuration providing a circular border or outermost concentric circle or shoulder 22a forming part of the recessed actual playing surface 14b as well as shelflike surface areas 22b. Continuing with FIGS. 1-3 and 5 in particular, except for the later described indicia of playing surface 14b, playing board 14 is completed by a countersunk central through opening 24 and a plurality of, preferably 32, upstanding stops, pins or pegs 26 having rounded upper ends and their lower ends embedded in board 14 and suitably secured thereto.

As shown in FIGS. 1, 3 and 4, the preferred inventive embodiment 10 includes a preferably wooden rotor 28 preferably in the form of a circular disc having a relatively large and generally sector-shaped slot 30 formed therein, and along the left inner side of which slot is arranged an elongated, flexible and resilient, preferably plastic detent 32 in the form of a strip suitably secured in place by screws 34. As is evident from FIG. 1, detent 32 extends beyond the outer periphery of rotor 28 and is engageable with stops or pins 26 for positively stopping the rotor between an adjacent pair of such stops for proper designation of the symbols to be selected, as described below. The rotor 28 is completed by a raised radial shoulder portion 28a along each side of the slot 30 to assist in manually spinning the rotor, with only the left shoulder being shown in FIG. 4, and a central through hole 28b (FIG. 3) aligned with hole 24 to receive the cylindrical shaft of a countersunk bolt 36, the outer or upper end of which is externally threaded to receive internally threaded cap nut 38 which is engaged over rotor 28 for rotatably mounting the same concentrically over the circles on game board 14. To facilitate such rotation, a small washer 40 is arranged between the rotor and nut, and a larger washer 42 is arranged between the rotor and playing surface portion 14b.

Turning now to FIG. 2 in particular, it is to be noted that playing surface 14b is provided with indicia formed thereon or therein in any suitable manner as by printing and/or engraving directly or indirectly on or in such surface, with such indicia including a plurality of, and preferably six, concentric circles 44 (seven including shoulder 22a) intersected by a plurality of, and preferably 32, radial lines 46 to form therebetween a multiplicity of, and preferably 160 segmental spaces 48 (192 including those outermost spaces 48a formed between shoulder 22a and radial line extensions 46a) and arranged preferably in 32 radial groups or sectors of five (six including those outermost) spaces each and five (six including those outermost) concentric circumferential rings of 32 spaces each. Likewise, arranged in each space 48 or 48a is a symbol.

As shown in FIG. 2 symbols in the spaces 48a of the outermost ring preferably are numbers and are arranged in numerical sequence preferably reading clockwise, from the number "1" through the number "32." The symbols in the five concentric rings below the outermost ring severally are in the form of specific alphabetical letters, such as "V," directly under numeral "1" in the outer word forming ring, or a characterization such as the key word "WILD" appearing, for example, in the outer word forming ring directly under the numeral "30," and designating any desired letter of the alphabet. While such symbols are arranged at random to normally avoid forming words, whether reading radially and/or circumferentially, they are arranged systematically as to frequency of appearance and generally in the ratio (5/21) of the number of vowels to the number of consonants in the English alphabet, whereby there is at least one vowel or "WILD" appearing in any four letters of each circumferential group exposable by slot 30 for selection, all in order to facilitate word formation. Likewise, the frequency of the characterization or key word such as "WILD" is controlled, there being preferably two such key words per concentric ring.

A preferred specific arrangement of symbols is set forth below in the following table, wherein the outer word forming ring (lying immediately within the outermost or numerical symbol bearing ring) through the inner word forming ring are referred to by the colors, black, red, blue, green and white respectively, these designations being arbitrarily selected purely for convenience of reference (although it is obvious that each ring on playing surface 14b including the outermost one) could be colored or not as desired.

RING FREQUENCY TABLE

Symbol	Black	Red	Blue	Green	White	Total
A	0	2	0	2	1	5
B	1	2	1	1	1	6
C	1	1	3	1	1	7
D	1	0	0	1	0	2
E	4	3	3	1	2	13
F	1	0	2	1	1	5
G	1	2	0	0	1	4
H	0	2	0	1	0	3
I	2	1	2	3	1	9
J	0	1	1	1	2	5
K	0	2	1	1	1	5
L	1	1	1	1	1	5
M	1	1	2	3	3	10
N	2	2	1	0	1	6
O	1	1	1	1	2	6
P	2	0	1	2	1	6
Q	0	1	0	0	1	2
R	2	0	3	1	1	7
S	3	1	1	1	0	6
T	0	3	2	0	3	8
U	1	1	1	2	2	7
V	2	1	0	1	1	5
W	2	0	2	3	0	7
X	0	1	0	0	1	2
Y	1	0	0	2	1	4
Z	1	1	2	0	1	5
"Wild"	2	2	2	2	2	10

Returning to FIGS. 1 and 2, it is to be noted that the numerical symbols "1," "2" etc., in the outermost ring on playing surface 14b are continuously exposed because they are located beyond the outer periphery of rotor 28, and are provided to designate the first, and also the second, third and fourth or last symbols in the remaining word forming rings or concentric circumferential groups thereof to be selected by the players upon successive rotations and stops of rotor 28 preferably in a radial sequence which is determined by indicia appearing on the upper surface of the rotor along each side of slot 30. As shown in FIG. 1, these latter indicia also are in the form of symbols arranged in radial groups or sectors severally aligned with the symbols in the concentric rings or circumferential groups thereof for severally designating such radial selection sequence. Preferably, the left radial symbolic

sequence group on rotor 28 forms the word "WHEEL" while that on the right of slot 30 forms the words "A WORD."

Hence, as shown in FIG. 1, should the sequence be radially inwardly, which is preferred, following the first spin of rotor 28, the word forming symbols in the outer ring, such as those lying directly beneath numerals "1," "2," "3" and "4" and between the letters "W" and "A" on the rotor, namely "V," "P," "U" and "W" are designated for selection from a multiplicity of playing pieces 50 (FIG. 6), a plurality of which are suitably provided for each exposed space and with symbols corresponding to the symbol in that space. As is evident, the rotor 28 is successively spun or rotated five times to start and complete the selection of preferably twenty letters, such total number being obtained by virtue of the fact that while the slot 30 is rotatable to uncover or expose upon stopping all of the symbols in each radial group, the number of radial groups exposed is predetermined by the number of symbols or spaces 48 in the rings or concentric circumferential groups thereof uncovered by such slot 30, and this turns out to be four symbols for each of the five spins, to make the total of 20 letters. This total has been found to be a convenient number to be accumulated prior to attempted formation of words therefrom, such as shown in FIG. 6. While the aforesaid radial inward sequence of five successive spins is the preferred mode of symbol selection, the radial sequence could be varied or eliminated, as desired. Moreover, since all twenty symbols of certain contiguous radial and circumferential groups are exposed per rotor spin, all the symbols could be selected following a single spin, thereby simplifying the game, such as for children.

Operation and Playing of Game

A player, and any desired number may play the game, spins rotor 28, noting upon stopping thereof the numeral in the outermost ring, beyond the outer periphery the rotor, underlying the projecting portion of detent 32 between an adjacent pair of stops 26, which are arranged along radial line extensions 46a, such as shown in FIG. 1. All players take the letter in the outer word forming ring directly below this designating numeral and the three letters to the right of the first chosen letter, as they appear between "W" and "A" on the rotor. Thus, if the detent stops at "20," all players take playing pieces 50 bearing the letters "N,G,N,E" and arrange these letters, as shown in FIG. 6. This operation is repeated four more times for outermost ring numerals "8, 5, 27 and 1" respectively, with the symbols in each next radially inwardly located circumferential group being selected sequentially until the innermost ring is reached, whereupon this last stopped position of rotor 28 appears in FIG. 1, with the selected letter bearing pieces 50 being arranged as in FIG. 6 for each player. All players now have 20 letters, and a "WILD" piece 50 is changed into any letter chosen by each player to make a word, by covering the "WILD" piece 50 with another piece 50.

Incidentally, these pieces 50 conveniently may be stored in any suitable manner, as in a separate compartmentalized container (not shown) or within the box, as on shelf portions 22b, if desired.

The object of the game is to make or spell as many words as possible in the shortest amount of time, with the longer words receiving higher points. The words formed may be crossed or independent as exemplified by the rearranged pieces 50 shown in FIG. 7, and various rules may be formulated, such as a time limit for making the words in a particular round of five spins, a game score of 100, bonuses for longest words, a range of points designated for individual letters depending upon the word length, penalties or no score for other than common ordinary words such as proper nouns, one or two letter words, misspelled words, letters left over, etc. The intriguing feature of the game is that the use of the inventive device 10 deter-

mines the letters from which the words actually are to be formed, with all players quickly and conveniently being given the same letters to begin with, as a result of the operation of the device. Thus, the game is started by all the competing players on an equal basis, unlike "SCRABBLE" for instance, or the game played with the aforesaid patented device, with the winner being determined solely by his or her skill and ingenuity in forming words within the rules.

It now will be seen how the invention accomplishes its various objectives, and numerous advantages thereof likewise will become apparent. Further, while the invention has been shown and described herein by reference to a single preferred embodiment, this is to be taken in illustrative rather than limiting sense, with the scope of the invention being determined by the appended claims.

What is claimed is:

1. A word forming game device wherein the improvement comprises: a board, a rotor mounted on said board and a multiplicity of playing pieces, said board having a playing surface 20 provided with concentric circles forming rings intersected by radial lines and defining spaces between said circles and radial lines, and pins severally arranged along said radial lines in an outermost ring beyond the periphery of said rotor, said spaces underlying said rotor bearing symbols severally indicating specific alphabetical letters or any desired alphabetical letter, said rotor being rotatable about its center which overlies the center of said circles, and having a sector-shaped slot adapted to expose upon stopping contiguous radial and circumferential groups of said underlying spaces, and a detent extending beyond the periphery of said rotor along one side of said slot 30 and engageable with said pins to stop said rotor and designate said groups of spaces exposed by said slot, and said playing pieces including a plurality for each exposed space, with said plurality for each space bearing symbols corresponding to the symbol in that space, whereby the designated ones of said symbols in said groups of exposed spaces are selected to form words by using said playing pieces bearing corresponding symbols.

2. The word forming game device of claim 1 wherein said symbols in said groups of exposed spaces severally are in the forms of specific alphabetical letters or a characterization indicating any desired alphabetical letter, but said symbols in any of said groups of exposed spaces normally do not form words, while in every one of said circumferential groups of exposed spaces there is at least one space bearing a symbol indicating a vowel or any desired alphabetical letter to facilitate the formation of words.

3. The word forming game device of claim 1 wherein said rotor is in the form of a circular disc and said sector-shaped slot exposes all of said spaces in a number of said radial groups, which number is predetermined by the number of said circumferential groups of spaces exposed by said slot, and said rotor is provided along at least one side of said slot with a radial group of symbols severally radially aligned with said symbols in said circumferential groups of exposed spaces for severally designating the radial sequence in which said symbols in said circumferential groups of exposed spaces are to be selected upon successive rotations and stops of said rotor.

4. The word forming game device of claim 3 wherein said symbols in said groups of exposed spaces severally are in the forms of specific alphabetical letters or a characterization indicating any desired alphabetical letter, but said symbols in any of said groups of exposed spaces normally do not form words, while in every one of said circumferential groups of exposed spaces there is at least one space bearing a symbol indicating a vowel or any desired alphabetical letter to facilitate the formation of words.
